UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A SPOON.

SPECIFICATION forming part of Design No. 22,243, dated February 28, 1893.

Application filed January 21, 1893. Serial No. 459,250. Term of patent 7 years.

To all whom it may concern:

Be it known that I, CHARLES OSBORNE, a citizen of the United States, residing at New York city, in the county and State of New York, have invented and produced a new and original Design for a Spoon, of which the following is a specification, reference being had to the accompanying drawings, forming part thereof.

10 Figure 1 shows the obverse of a spoon with a handle of my improved design; and Fig. 2 is the reverse of the same.

Similar figures of reference indicate corresponding parts in both views.

15 My design relates to spoons and similar articles, and is embodied in the handle thereof. The handle has a substantially straight shank 10, which has a longitudinal central depression on both the obverse and reverse, and at 20 the top the shank is widened, as shown at 11, this widened portion being convex on the obverse and concave on the reverse sides. The plain effect of the widened portion is broken by fringe-like figures 11^a, which are produced

25 on the widened portion near its junction with the straight part of the shank. The edges of the shank and of the flattened portion of the handle are formed into raised rib-like figures

12, which are broken at intervals by leaf-like figures 13, which fold over the obverse and reverse sides of the handle. At the top of the handle is produced a flower-like figure 14, in the shape of an open fan, the larger end being upon the widened portion of the handle, and the smaller end being scalloped, as shown 35 at 15, and forming the top end of the handle. At the lower end of the handle on the obverse side is a flower-like figure 16, very similar in shape to the figure 14 described above, and around the edge of this figure is a foliated 40 fringe or border 17. On the reverse side of the handle at its lower end, is another flower-like figure 18, also of fan shape, the larger end being made to overlap the spoon bowl or similar part to which the handle is attached. 45 The flower-like figure 18 is provided with a foliated border 19, which merges in scrolls 20, arranged on opposite edges of the flower-like figure 18.

I claim—

50 The design for a spoon, herein shown and described.

CHARLES OSBORNE.
